GLASS POLISHING TOOLS

Frederic Barnes Waldron, Prescot, England, assignor to Pilkington Brothers Limited, Liverpool, England, a company registered under Limited Liability Company's Acts

Application May 11, 1934, Serial No. 725,146
In Great Britain May 19, 1933

2 Claims. (Cl. 51—120)

This invention relates to polishing tools for flat glass and has for its object an improved form of polishing tool.

In the specification of Letters Patent No. 5 1,946,955 there is described and shown a polish-tool frame comprising a plurality of tools in which the whole polish-tool frame is pressed against the glass by pressure applied to the frame, and this total pressure is distributed between 10 the individual tools in any desired proportion by means of a mechanical linkage.

According to this invention, which is an improvement in or modification of that claimed in the specification of the above mentioned Patent 15 No. 1,946,955, each tool is the moving element of a hydraulic press, while the liquid chambers of all the presses are connected together to form a closed system, which is substantially filled with liquid so that while each individually can yield, 20 the operative surface as a whole is substantially non-yielding.

The polishing tool frame is preferably provided with means for varying the amount of liquid in the closed system, whereby the position of the 25 tools as a whole can be adjusted in a direction perpendicular to the glass.

In the accompanying drawing:—

Figure 1 is a horizontal view of a polishing tool frame with four tools (of which only two are 30 shown), looking upwards and showing the parts above the line A—A of Figure 2, and

Figure 2 is a vertical section through the line B—B of Figure 1, showing diagrammatically the means of water supply.

The drawing shows a polishing tool frame of the type in which a frame 1 fixed on a shaft 2, which is adapted to be rotated, carries four tools 3, 3, in the form of felt-covered discs. The line 4 indicates the under-surface of the glass being polished. Each tool 3 has a shaft 5 which is free to rotate in the bearing 6 and is supported on a thrust bearing 7 of which the lower member is attached to the flexible disc 8 held by the ring 9 to the casing 10, which also is supported by the frame 1. Each tool therefore is free to rotate, and to move up and down in its bearing 6 insofar as the flexible disc 8 permits.

A pipe 11 communicates with each casing 10, 50 and the four pipes 11 are connected together by a ring pipe 12. This ring pipe is connected by a pipe 13 with a hole 14 in the shaft 2, and the hole 14 is connected through a stuffing box 15 on the bottom end of the shaft, with a stationary pipe 16 connected to a water main 17 of

moderate pressure through a valve 18, and connected to a discharge valve 19.

The operation of the device is as follows:— 5 the discharge valve 19 being closed, water is admitted by the valve 18, through the pipe system 16, 14, 13, 12, 11, to all the casings 10, and by the yielding of the flexible discs 8, moves the tools 3 upwards. When the tools have reached their correct working position the valve 18 is closed and, the water system then being closed, 10 the water supports the four tools as a whole against any pressure between the glass and the tools. This pressure produces a certain pressure per square inch in the water system which, under normal conditions, is equal in all the casings 10, 15 and therefore ensures that the pressure on the glass of all the tools (assuming these to be of equal size) is the same.

Any one tool is free to yield to unevennesses in the glass, water being driven to, or taken from, 20 the casings of the other tools, so as to maintain equality of pressure among the tools.

The pipes of the system connecting the casings 10 should be of such a size, having regard to the unevennesses of the glass, that appreciable temporary variations in pressure are not caused by 25 restriction of the flow of water.

The height of the tools can be raised or lowered by opening valves 18 or 19 respectively. Further, the whole polishing tool can be rendered inoperative (for instance, when introducing glass into the apparatus) by opening valve 19 fully to allow the tools to fall by their weight below their operative position, and this avoids the necessity of constructing the frame of the polishing tool so that 35 it can be raised or lowered. If the apparatus be used for glass in a vertical plane, the movement of the tools away from the glass can be secured either by spring pressure or by withdrawing water from the system. 40

Any form of hydraulic press, for instance, a cylinder with plunger, can be used instead of the casings 10 with flexible discs 8. Since oil or other liquid can be used in place of water, the word "hydraulic" in the specification and claims is to 45 be understood as including liquids other than water.

Any convenient number of tools may be carried on each polishing tool frame and, where the tools are of different sizes, the relative pressures of 50 the different tools on the glass may be given any desired values by varying the areas of the flexible discs 8.

Instead of connecting the water system externally to a water main, a motor driven pump capa- 55

ble of supplying or withdrawing water to or from the system, from or to a small reservoir, may be mounted on the polishing tool frame.

Having described my invention, I declare that 5 what I claim and desire to secure by Letters Patent is:—

1. Polishing runner comprising a rotating frame, a plurality of polishing tools mounted thereon and adapted to slide in a direction perpendicular to their operative surfaces, a plurality 10 of hydraulic presses mounted on the frame, a

connection between the movable member of each press and each polishing tool respectively, a communication between the liquid chambers of all the presses and means for preventing during operation of the runner, the flow of liquid to and from the system comprising the liquid chambers and their communications. 5

2. Polishing runner as in claim 1, comprising means for adjusting to a predetermined value the average height of the tools relative to the frame. 10
